INVENTOR
David H. Green
BY
M. C. Frank
ATTORNEY

UNITED STATES PATENT OFFICE.

DAVID H. GREEN, OF SAN FRANCISCO, CALIFORNIA.

CORN FILE.

Application filed January 9, 1923. Serial No. 611,559.

To all whom it may concern:

Be it known that I, DAVID H. GREEN, a citizen of the United States, residing at San Francisco, in the county of San Francisco and State of California, have invented certain new and useful Improvements in Corn Files, of which the following is a specification.

This invention relates to toilet articles, and in particular to a corn file for reducing corns or callosities, such as usually occur on the feet and the hands.

It is customary to use a file or a knife on such callosities to remove the horny or outer layers of dead skin therefrom. At present this is best done with a file, as a knife is liable to slip and inflict serious wounds, especially if in inexpert hands.

Files and other abrasive articles for this purpose, become dulled and clogged with particles of the dead skin and so lose efficiency, and finally fail entirely in the performance of their expected function.

It is the chief object of my invention to produce a corn file of simple construction and operation, whose abrading surface can be easily renewed, even by an inexpert user and as often as desired, and thus be maintained at its maximum efficiency for useful service.

I will now describe the construction of such an article, illustrating the same in the accompanying sheet of drawings, in which:—

Figure 1 is an elevation of the corn file from the broad side.

Figure 2 is an elevation of it from the narrow side and at right-angles to Fig. 1.

Figure 3 is a cross-section taken at any point of the active part, as at the line A—A of Fig. 2.

I will describe the article as made with emery cloth as the abrasive, that being a material easily procurable.

Referring to the drawing and the figures thereof:—A foundation or base of oblong cross-section and rounded at the corners, is formed with a handle 1 at one end, and with a tongue 2 at the other end.

This base is preferably of straight-grained wood, having resilient properties

that tend to pinch when a long kerf is cut therein, such as exhibited by hickory or ash.

The tongue 2 is split with the grain of the wood, in a plane substantially parallel to its broader sides, as seen at 3 in Figs. 2 and 3, thus dividing it into two strips 4 and 5. The tongue member is tapered from its joinder with the handle member to the free end, which is rounded or otherwise ornamenteally configured.

About one of the strips of the tongue member as 4, is wound a piece of emery cloth 6, with any desired number of turns, (three are shown). After making the desired number of winds on the strip 4, the cloth is carried over the edge of strip 5 and across its outer flat surface to the opposite edge and there turned in, and the edge of the cloth inserted into the split 3, as seen at 7, more especially in Fig. 3.

The manner of use of the toilet article on a corn is similar to that of ordinary files, and is too well known to need description. When the abrasive particles on the cloth become dulled, from the breaking of their sharp edges and corners, or become clogged with dead skin, the emery cloth may be slipped off the base member 2, and recoiled to bring fresh surfaces to the outside, and then slipped onto the strips of the tongue member again. The tongue member being tapered, the emery cloth may be slipped back upon it till it binds on the taper sufficiently for practical purposes. The resilience of the wood or other material composing the base, will cause it to bind against the portions of cloth in the split 3, and thus prevent any unrolling thereof or slipping.

Having thus illustrated and described my invention, what I claim as new and desire to secure by Letters Patent of the United States is the following:

1. A toilet article in the form of a corn file, composed of a resilient material having a handle at one end and an active member at the other end, said active member being tapered and of oblong cross-section, and split longitudinally in a plane substantially parallel to its broader sides, and an abrasive fabric encircling said active member and having its edges turned into the said

split and held therein by the pinching re-
action of the said resilient material.

2. A toilet article in the form of a corn
file, composed of a resilient material hav-
ing a handle at one end and a tongue at the
other end, said tongue being tapered and
split longitudinally into two strips, and an
abrasive fabric wound about one of said

strips with a plurality of turns and carried
around the other strip and having its edge 10
engaged in said split, said fabric adapted to
be unwound from said first strip and re-
wound on said second strip, thereby present-
ing fresh abrasive surfaces.

In testimony whereof I affix my signature.
DAVID H. GREEN.
